DESIGN FOR A SLIPPER

Leon Goldberg, New York, N. Y.

Application April 9, 1936, Serial No. 62,034

Term of patent 3½ years

To all whom it may concern:

Be it known that I, Leon Goldberg, a citizen of the United States of America, residing in city of New York, county of New York, and State of New York, have invented a new, original, and ornamental Design for a Slipper, of which the following is a specification, reference being had to the accompanying drawing, forming part thereof.

Fig. 1 is a plan view of a slipper showing my new design.

Fig. 2 is a perspective view of a slipper as shown in Fig. 1.

An essential feature of my design resides in ornamenting the vamp of a slipper by means of the type of doll's face, as disclosed.

I claim:

The ornamental design for a slipper substantially as shown and described.

LEON GOLDBERG.
